United States Patent Office

Des. 203,342
Patented Dec. 28, 1965

203,342

COMBINED TELEVISION RECEIVER AND PRINTER

Edward L. Byer and Jack L. Stark, Fort Wayne, Ind.,
assignors to International Telephone and Telegraph
Corporation, Nutley, N.J., a corporation of Maryland

Filed May 26, 1964, Ser. No. 80,155

Term of patent 14 years

(Cl. D26—14)

Fig. 1

FIGURE 1 is a perspective view of the front and one side of a combined television receiver and printer showing our new design;

FIGURE 2 is another perspective view of the front and other side of our combined television receiver and printer; and

FIGURE 3 is a rear view of the combined television receiver and printer of FIGURES 1 and 2.

The dominant features of our design reside in those portions shown in full lines on the drawing.

We claim:

The ornamental design for a combined television receiver and printer, as shown and described.
